UNITED STATES PATENT OFFICE.

ANGUS McMILLAN, OF OAKLAND, CALIFORNIA.

MITER BOX.

Application filed September 25, 1924. Serial No. 739,767.

To all whom it may concern:

Be it known that I, ANGUS McMILLAN, a citizen of the United States, and a resident of the city of Oakland, county of Alameda, and State of California, have invented a new and useful Miter Box, of which the following is a specification.

My invention relates to a miter box and particularly to a folding miter box.

10 An object of my invention is to provide a folding miter box which may be conveniently transported and quickly set up for use.

Another object of the invention is the provision of a miter box which, in knocked down form, provides a casing in which the demountable elements of the device may be carried.

20 My invention possesses other objects and features of advantage, some of which with the foregoing will be set forth in the following description of the preferred form of my invention which is illustrated in the drawings accompanying and forming part of the specification. It is to be understood that I 25 do not limit myself to the showing made by the said drawings and description, as I may adopt variations of the preferred form within the scope of my invention as set forth in the claims.

30 Referring to the drawings:

Figure 1 is a front elevation, and Figure 2 is a plan view of the miter box of my invention. Figure 3 is a cross sectional view, the plane of section being indicated by the 35 line 3—3 of Figure 1. In Figure 1 the miter box saw is shown in cross section, and in Figures 2 and 3, the saw is indicated by dotted lines.

Figure 4 is a plan view of the open casing, 40 showing the demountable elements of the miter box within.

Figure 5 is a vertical transverse sectional view on a larger scale of the closed inverted casing, the dotted lines indicating the position of the lid when the miter box is set up. The plane of section is indicated in Figure 4 by the line 5—5.

Figure 6 is a horizontal sectional view of a part of the slideway and the bracket slidably mounted thereon. The plane of the section is indicated by the line 6—6 of Figure 1.

50 Broadly my invention comprises a miter box which may be folded to form a closed casing of relatively small compass. When the casing is inverted the bottom provides

the floor of the miter box, the sides of the casing the supporting walls for the floor, and the lid of the casing may be turned backwardly against the rear wall of the 60 casing to form the rear upstanding wall of the miter box. Means are provided for demountably securing the movable parts in their respective functional positions, and demountable means are provided for holding the miter saw, and for setting it at different angles.

In greater detail my invention comprises a casing, the bottom 11, rear wall 12 and ends 13 of which are preferably formed of 70 a single piece of sheet metal. The ends 13 are provided with an outwardly bent flange 14, having apertures 15 therein for securing the miter box in position. The front wall 16 is preferably a casting provided with 75 flanges 17 to facilitate securing it to the ends of the casing by suitable rivets. The rear wall 12 is preferably reinforced at its junction with the bottom by angle braces 18, and is divided in the center by a slot, bridged by the bearing bracket 20 disposed between and rigidly secured to the adjacent ends of the divided wall.

Secured to the inner side of the rear wall in any suitable manner, such as by rivets, 85 are a plurality of reinforcing plates 22, each having a tongue bent thru the casing to form the leaf 23 of a hinge, the other leaf of which is formed by the tongue 26, which extends from the flanged reinforcing rib 28 90 riveted on the lid 29.

In order to permit passage of the saw in the miter box form of my device, the lid 29 thus pivotally mounted, is formed of two pieces of sheet metal which are held in spaced relation by the hinges and by the bridge 31. The lid may serve as a cover for the casing as shown in Figure 5, or it may be turned backwardly against the rear wall 12 to form the upstanding rear wall 100 of the miter box as shown in Figures 1 and 2.

I provide means for holding the lid in this latter position comprising screws 32 with wing nuts 33, and piercing the rear wall 12 of the casing. The screws have flattened heads 34 to permit passing thru and engagement with the sides of the elongated slots 36 in the lid. The security of the upstanding wall of the miter box is increased by passing the screws 32 thru the reinforcing plates 22 and the ribs 28 which are conveniently placed for this purpose. The lid

is held in the closed position by a screw set in the wall 16 and having a head 37 flattened on one side. The outer adjacent corners of the lid parts are notched to provide a recess 38, so that the lid will pass over the screw head 37, which may then be given a half turn to seat the head on the edges of the notches.

A slideway 41 is mounted on the casing 10 wall 16, and is provided with a plurality of apertures 42, placed at predetermined points. The slideway serves as a mounting for the bracket 43, and on one side has a clamping screw 44 which impinges upon the 15 resilient wear plate 45, and on the other side a spring pressed stop pin 46, for fixing the position of the bracket. The stop pin 46 is adapted to engage in the apertures 42 in the slideway to accurately position the bracket 20 at predetermined points so that the saw 47 may be positioned in the box at certain commonly used angles such as 15°, 30° and 45° on each side of the 90° position.

A saw guide socket 51 is carried on the 25 bracket 43 and the saw guide spindle 52 is mounted in the socket 51. The saw guide is of the usual type, and has the adjusting screw 53 for determining the height of the saw from the floor of the miter box. An 30 arm 54 is provided on the socket adjacent the bracket, and this arm extends under the floor of the miter box, telescoping with the arm 56 on the bracket 57, pivoted on the bearing 20. The telescoping arms serve to 35 insure perfect alinement of the saw guide so that there is no tendency for the saw to jam in the guides, and they also stiffen the saw guides, so as to maintain parallelism between them.

40 The bracket 57 is demountably held in position on the bearing in any suitable manner such as by the wing screw 58, which is locked by the set screw 59. A saw-guide socket 60 similar to the socket 51 is fixed in 45 the bracket 57, and contains a spindle 61 similar to spindle 52. The miter saw may be placed in the saw-guides, adjusted and set at any desired angle, and used in the customary manner. A protective layer 62 50 of wood, leather, or other non-metallic material, is preferably secured to the outer surface of the bottom wall 11, by means of screws 63.

55 My invention provides a compact casing of relatively small compass in one form, and a large and accurate miter box in another form. It is particularly valuable to carpenters and interior wood workers who are constantly moving from one job to another. 60 It is conveniently transported, and since the demountable parts are all carried in the closed casing, it can be quickly set up, when needed.

I claim:

65 1. A folding miter box comprising a cas-

ing, a lid adapted in one position to close the casing and in another position to project beyond the plane of the bottom of the casing to form the vertical wall of the miter box, and means for mounting a saw on said 70 box.

2. A folding miter box comprising a casing, a lid adapted in one position to close the casing and in another position to project beyond the plane of the bottom of the 75 casing to form the vertical wall of the miter box, and adjustable saw guides mounted on said casing.

3. A folding miter box comprising a casing having a lid pivoted thereon and normally closing said casing, said lid also being adapted to be turned to project beyond the plane of the bottom of the casing to form the vertical wall of the miter box, means for fixing the lid in the vertical wall position, 85 and means for adjustably mounting a saw on said box.

4. A folding miter box comprising a casing having a lid pivoted thereon and normally closing said casing, said lid also being 90 adapted to be turned to project beyond the plane of the bottom of the casing to form the vertical wall of the miter box, means for fixing the lid in either position, and means for adjustably mounting a saw 95 on said box.

5. A folding miter box comprising a casing having a lid pivoted thereon and normally closing said casing, said lid being 100 adapted to be turned from the closed position to a position against the rear wall of the casing to project beyond the plane of the bottom of the casing to form the vertical wall of the miter box, and means for clamping the lid to the rear wall.

6. A folding miter box comprising a casing having a lid pivoted thereon and normally closing said casing, said lid being adapted to be turned from the closed position to a position against the rear wall of the 110 casing to project beyond the plane of the bottom of the casing to form the vertical wall of the miter box, and means carried in the rear wall for clamping the lid to the rear wall.

7. A folding miter box comprising a casing having a slotted lid arranged thereon and normally closing said casing, said lid being adapted to be moved from the closed position to a position against the rear wall of the casing to project beyond the plane of the bottom of the casing to form the vertical wall of the miter box, and bolts mounted in the rear wall of the casing and having flattened heads adapted to pass thru the slots 120 in the lid and hook over the edges thereof for securing the lid to said rear wall.

8. A folding miter box comprising a casing having a bottom forming the floor of the miter box when the casing is reversed 125

and a pivoted lid adapted to be turned to form the rear wall of the miter box, and means for adjustably mounting a saw on said box.

5 9. A folding miter box comprising a casing having a bottom forming the floor of the miter box and a pivoted lid adapted to be folded backwardly to form the rear wall of the miter box, a slideway mounted 10 on the front wall of the casing, a demountable bracket slidably arranged on said slideway, a demountable bracket pivotally arranged on the rear casing wall, and means for adjustably mounting a saw in said 15 brackets.

10. A folding miter box comprising a casing having a bottom forming the floor of the miter box and a lid adapted to be moved to project beyond the plane of the bottom 20 of the casing to form the rear wall of the miter box, a slideway mounted on the front wall of the casing, a bracket slidably carried on said slideway, means for setting and fixing the position of the bracket on the slide- 25 way, a front saw-guide socket pivotally mounted on said bracket, a second bracket pivotally carried on the rear casing wall, a rear saw-guide socket disposed on said second bracket, means for maintaining alignment 30 of said sockets, and a saw-guide spindle mounted in each socket.

11. A folding miter box comprising a casing having a bottom forming the floor of the miter box and a lid adapted to be moved to project beyond the plane of the bottom 35 of the casing to form the rear wall of the miter box, a slideway mounted on the front wall of the casing, a bracket slidably carried on said slideway, means for setting 40 and fixing the position of the bracket on the slideway, a front saw-guide socket pivotally mounted on said bracket and provided with an arm extending under the floor of the miter box, a second bracket pivotally carried 45 on the rear casing wall, a rear saw-guide socket disposed on said second bracket

and provided with an arm telescoped with the arm on said front saw guide socket, and a saw-guide spindle mounted in each socket.

12. A folding miter box comprising a casing having a bottom forming the floor of the miter box and a pivoted lid adapted to be turned backwardly to form the rear wall of the miter box, a slideway mounted on the front wall of the casing, a bracket slidably carried on said slideway, a stop pin adjustably interposed between the bracket and slideway to position the bracket on the slideway, means for clamping the bracket to the slideway, a front saw-guide socket 50 pivotally mounted on said bracket and provided with an arm extending under the floor of the miter box, a second bracket pivotally carried on the rear casing wall, a rear saw-guide socket disposed on said second bracket 55 and provided with an arm telescoped with the arm on said front saw-guide socket, and saw-guide spindles mounted in said sockets.

13. A miter box comprising a casing having a lid formed with a transversely disposed slot, said lid forming a closure for the casing and adapted to be moved to project beyond the plane of the bottom of the casing to form the vertical wall of the miter box, means for fixing the lid in the vertical 75 wall position, and means for mounting a saw on said casing to operate thru said slot.

14. A miter box comprising a casing having a lid formed with a transversely disposed slot, said lid forming a closure for the casing and adapted to be moved to project beyond the plane of the bottom of the casing to form the vertical wall of the miter box, means for fixing the lid in the vertical wall position, saw-guide means demountably 80 pivotally arranged adjacent said slot, and saw-guide means slidably arranged on the opposite side of the structure.

In testimony whereof, I have hereunto set my hand.

ANGUS McMILLAN.
